UNITED STATES PATENT OFFICE

95,823

DESIGN FOR A SHOWER HEAD

Chester W. Hathaway and Ernest Krumsiek, Decatur, Ill., assignors to Mueller Co., Decatur, Ill., a corporation of Illinois

Application April 1, 1935, Serial No. 56,176

Term of patent 14 years

To all whom it may concern:

Be it known that we, Chester W. Hathaway and Ernest Krumsiek, citizens of the United States, residing at Decatur, county of Macon, State of Illinois, have invented a new, original, and ornamental Design for Shower Head, of which the following is a specification, reference being had to the accompanying drawing, forming a part thereof.

We claim:

The ornamental design for a shower head substantially as shown.

CHESTER W. HATHAWAY.
ERNEST KRUMSIEK.
